UNITED STATES PATENT OFFICE

2,079,766

HYDRAULIC MACHINE

George A. Jessop and Torleif Norbom, York, Pa.,
assignors to S. Morgan Smith Company, York,
Pa., a corporation of Pennsylvania

Application January 4, 1937, Serial No. 118,950

2 Claims. (Cl. 253—117)

This invention relates to hydraulic machines, such as hydraulic turbines, pumps, and the like, and more particularly to the type of hydraulic machines having runners with movable or adjustable blades.

5 For installation at the Bonneville Power and Navigation Project, Columbia River, between the States of Oregon and Washington, are adjustable blade hydraulic turbines having runners with a diameter of 280 inches. These runners are the 10 largest ever built up to the present time, and in order to permit desired operation of the units, certain features have been included in the construction of the runners.

As is well-known in the art, the hub of an adjustable blade runner is filled with oil for lubricating the blade operating mechanism within the hub. During operation water leaks through the joints between the blades and the hub proper and such water collects in the bottom of the 20 hub. Obviously some means should be provided for removing water from the hub, since an excess of water therein, mixing with the lubricating oil, will destroy the lubricating properties of the oil. Therefore, the present invention relates more 25 particularly to means for removing water from the bottom of the runner hub without the necessity of dismantling the runner or unwatering the draft tube.

An object of the invention is to provide improved means by which water can be withdrawn from the bottom of the hub of an adjustable blade hydraulic turbine.

Another object of the invention is to provide an improved adjustable blade hydraulic turbine 35 in which the operating rod of the blade operating mechanism is so formed as to constitute a tube adapted to be brought into registration with an extensible member mounted in the main shaft of the turbine so that water can be removed from 40 the hub of the turbine.

With the foregoing and other objects and advantages in view, the invention consists in the construction and arrangement of the several 45 parts which will be hereinafter more fully described and claimed.

In the accompanying drawings:—

Figure 1 is a view partly in section of an adjustable blade hydraulic turbine embodying the 50 present invention;

Fig. 2 is an enlarged vertical section of the runner hub showing the blade operating mechanism in mid-position;

Fig. 3 is an enlarged vertical section of the 55

servo motor for operating the runner blade operating mechanism;

Fig. 4 is an enlarged vertical section of the extensible member shown in Fig. 3, the member being disconnected from the operating rod; and

Fig. 5 is a view similar to Fig. 4 showing the 5 extensible member operatively connected with the operating rod.

Referring to the drawings and especially to Fig. 1, the turbine comprises a runner 11 fixed to the lower end of a shaft 12, the lower end of 10 said shaft being supported by a bearing 13 mounted in the casing of the turbine.

A suitable number of blades 15 are rotatably supported in the hub 14 of the runner 11 and project radially therefrom.

The inner end of each blade 15 is formed with a trunnion 16 which is journaled in bearings 17 and 18 mounted in the hub of the runner 11.

Means are provided for simultaneously rotating 20 all of the blades 15 and for maintaining them in equal angular relationship, such means comprising preferably a lever 19 rigidly fixed on the trunnion 16 of each blade and links 20 which connect the levers on the different blades to a cross head 21 fixed to the lower end of an operating rod 22 which extends upwardly through the hollow runner shaft 12.

The lower portion of the cross head 21 is formed with a downwardly projecting tubular extension 23.

30 Mounted in the bottom portion of the hub 14 is a member 24 having a central cylindrical portion 25 for the reception of the tubular extension 23 of the cross head 21.

The main body of the member 24 is also cylindrical in form and this main body portion of said member surrounds the central cylindrical portion 25 so as to provide a space through which fluid in the runner hub can easily flow. The vertical walls of the main portion of the member 24 and the central portion 25 are connected at suitable intervals by webs 26, as shown in Fig. 2.

The bottom 27 of the member 24 is semi-spherical in cross section so as to provide a sump 30 in which any water which may seep into the link of the runner can collect. An opening 28 is formed in the lowermost part of the bottom 27 and a valve diagrammatically indicated at 29 (Fig. 2) is employed to normally close opening 28.

40 The lower end of the operating rod 22 extends downwardly below the cross head 21 and terminates within the sump 30.

45 A vertical bore 31 is formed in the operating rod 22. This bore terminates a suitable dis-

15

30

35

40

45

50

55

tance from the upper end of the operating rod, as shown in Fig. 3.

A horizontal bore 32 formed in the operating rod 22, intersects the vertical bore 31 and constitutes a port, the purpose of which will be hereinafter more fully described.

As shown in Fig. 3, the upper end of the operating rod 22 is fixed to the piston 33 of a servo motor 34 which is mounted between the upper 10 end of the runner shaft 12 and the lower end of the shaft 35 of an electric generator or other mechanism (not shown) adapted to be driven by the turbine.

In mechanisms falling within the scope of the 15 present invention, the controlling fluid is generally oil, means being provided for controlling the oil in such a manner as to operate piston 33 so that the blades are rotated in the desired manner through the connection between said 20 piston and the blade operating mechanism within the hub 14 of the runner afforded by rod 22.

One type of mechanism which has gone into 25 extensive use is disclosed in McCormack Patent No. 1,937,772, granted December 5, 1933, for Hydraulic turbine.

The servo motor piston 33 is contained in a suitable cylinder, the upper portion of which is closed by the lower portion of the generator shaft 35.

The upper portion of the operating rod 22 passes through a bushing 36, and this bushing besides forming a bearing for the operating rod 22, provides means for closing the chamber 37 on the lower side of the piston 33.

The oil used for controlling the operation of piston 33 is somewhat lighter in viscosity than the lubricating oil within the runner hub and the bushing 36 tends to keep the light operating oil from mixing with the heavy lubricating oil.

The servo motor piston 33 is double acting, and 40 in order to supply oil to both sides thereof for the purpose of operating the same in both directions, two tubes or pipes 38 and 39 are employed. These pipes are mounted within the hollow generator shaft 35 and rotate therewith, said pipes 45 extending from the servo motor 34 upwardly through the generator to a head which is operatively connected with a control device associated with the governor of the turbine in the manner fully described in the above-referred-to McCormack patent.

The lower end of pipe 39 is in communication 50 with chamber 37 on the lower side of the servo motor piston 33, and the lower end of pipe 38 is in communication with chamber 40 on the upper side of piston 33, as shown in Fig. 3.

During operation of a hydraulic turbine of the type herein described, water seeps into the hub 14 through the joints where the runner blade trunnions enter the hub. This water collects in 60 the sump 30, and it is desirable that the water be removed from time to time.

According to the present invention we have provided means which are mounted in the runner shaft 12 and adapted to be operatively associated 65 with the port 32 in the rod 22 so that communication will be established with the sump 30 whereby the water in the bottom of the runner hub can be withdrawn from the sump.

Through the operation of servo motor piston 70 33, the operating rod 22 is reciprocated, and consequently it is necessary to shut down the turbine in order to remove water from the runner hub.

The lower end of the operating rod 22 is formed 75 with a downwardly extending portion 42 which

projects into the member 24. During the reciprocating movements of rod 22, the lower portion 42 thereof moves upwardly and downwardly in sump 30. The vertical movement of rod 22 is obviously limited, since the runner blades are normally moved or turned through a limited angle during operation of the turbine, and in its downward movement the lower end of the rod 22 approaches the bottom of sump 30 only when the runner blades 15 are turned to wide-open position. 10 The position of the parts shown in Figs. 2 and 3 is the intermediate position of the runner blades.

At a suitable point, a horizontal opening 43 is 15 formed in runner shaft 12.

Mounted in opening 43 is an extensible member in the form of a plunger 44 having a central longitudinal bore 45 formed therein, the bore 45 being adapted to align with bore 32 heretofore referred to when the operating rod 22 is 20 in its lowermost position, in which position the lower end 42 of said rod is disposed adjacent the bottom of the sump 30, as shown by dotted lines, Fig. 2.

Lubricating oil is present in the space 46 in 25 the central bore of shaft 12 in which the rod 22 is disposed, and, therefore, when the plunger 44 is operatively connected with bore 32 a tight seal should be provided so that only the fluid in the sump will flow through the plunger. Accordingly, the outer end of bore 32 is formed with a tapered seat 47, against which is adapted to seat the correspondingly formed inner end 48 of the plunger 44 (see Fig. 5).

During operation of the turbine, the plunger 35 44 is retracted from the rod 22 so as to permit free movements of said rod.

For the purpose of moving the plunger 44 inwardly when it is desired to connect same with the bore 32 of the rod 22, said plunger is mounted in a nut 49 having external screw threads 50 engaging threads 51 formed in an enlarged portion 52 of the bore 43.

The outer end of the plunger 44 is provided with a ball head 53 having a central opening 54 45 formed longitudinally therein, in alignment with the bore 45 of plunger 44.

The nut 49 is formed with a seat 55 for the ball head 53, the construction being such that the plunger 44 is free to swing about the joint 50 provided by head 53 and seat 55 so that the inner end of said plunger will tightly seat against seat 47 when the plunger is moved inwardly into engagement with the rod 22.

Communication through the plunger is normally closed by a valve 56 carried by a guide 57 mounted in the plunger, said guide having one or more openings 58 formed therein for the purpose of permitting fluid to flow through the plunger when the valve 56 is unseated.

The valve 56 is normally held against a seat 59 formed in the head 53, by an expansible coil spring 60.

The outer end of nut 49 is formed with notches 61 for the reception of a suitable spanner wrench (not shown), by which the nut is adapted to be screwed inwardly and outwardly in order to move the plunger 44 towards and away from the rod 22.

A retainer 62 is mounted in an enlarged portion 63 of opening 43, said retainer having an inner threaded portion 64 engaging the threads 50 of nut 49, and an outer internally threaded portion 65.

When the plunger 44 is retracted from its en- 75

gagement with rod 22, a plug 66 is mounted in the threaded portion 65 of the retainer 62, as shown in Fig. 4, so as to close the outer end of the plunger and protect the valve 56.

5 When it is desired to drain water from the sump 30, the turbine is shut down, and the blade operating mechanism is then moved to the position in which plunger 44 alines with bore 32.

10 Plug 66 is then removed so as to expose the outer end of the plunger 44. The nut 49 is then screwed inwardly, so as to move the plunger 44 from the position shown in Fig. 4 to the position shown in Fig. 5.

15 A nipple 67 having its inner end formed with threads which will fit the threads 65 of the retainer 62 is next fastened to the retainer, as shown in Fig. 5. Nipple 67 is formed with a suitable inwardly projecting wire loop 68 which is adapted to extend through the opening 54 in 20 the ball head 53 and unseat the valve 56.

25 After the nipple 67 has been attached to the retainer 62, a hose (not shown) may be attached to the outer threaded portion of the nipple, to carry off the water drained from the sump 30.

30 In some installations the lubricating oil within the runner hub 14 may be maintained at a predetermined pressure, as described, for instance, in our prior application for Letters Patent for Hydraulic turbine, Serial No. 37,349, filed in the United States Patent Office August 22, 1935, now Patent No. 2,070,601, dated February 16, 1937. In such case, when the valve 56 is unseated, the pressure of the oil within the runner hub will force the fluid in the sump 30 upwardly through the bore 31 and outwardly through the plunger 44 and the hose connected to nipple 67.

35 However, in installations in which the lubricating oil within the runner hub is not maintained under pressure, it may then be necessary to connect a pump to the hose which is fastened to nipple 67 in order to drain the fluid from the sump 30.

40 Obviously, the bore 31 in the operating rod 22 is filled with lubricating oil from the runner hub. Therefore, when the valve 56 is unseated, oil will first flow outwardly through plunger 44 ahead of the water which is being drained from the sump 30.

45 It has been described that the present invention covers the design of hydraulic turbines installed at the Bonneville Power and Navigation Project. The length of the bore 31 of these turbines is approximately 20 feet and the diameter of said bore is approximately 1 3/4 inches, so that the cubic contents of this space within the operating rod is approximately 2.5 gallons. This quantity of oil must be drained away before it can be determined whether or not there is water in the sump 30. 50 This quantity of oil, however, is a small matter compared with the quantity of oil contained in the runner hub and the bore 46 of the runner shaft 12, and the loss of this small amount of oil is not serious.

55 After the water has been removed from the sump 30, the nipple 67 can be detached from the retainer 62, and the valve 56 will automatically close the communication through the plunger 44.

60 The nut 49 can then be screwed outwardly there-

by withdrawing the plunger away from the operating rod 22, after which the plug 66 can be replaced in the retainer 62.

65 From the foregoing it will be noted that by the present invention it is only necessary to shut down the turbine and connect the plunger 44 with the operating rod 22, in the above-described manner, in order to dewater the runner hub. Heretofore, in order to remove the water from the hub it was necessary to unwater the draft tube 10 and enter the draft tube below the runner in order to open valve 29. By this invention the time required to drain water from the hub is considerably expedited, since this work can be conveniently performed more frequently than by the 15 prior methods and by merely shutting down the turbine for a short period of time.

Having thus described our invention, what we claim is:—

1. In a hydraulic machine, a runner having a 20 hollow hub with a sump in the bottom thereof, a plurality of blades rotatably mounted in said hub, mechanism within the hub for rotating the blades, a hollow shaft connected to the hub, an operating rod reciprocatably mounted in said shaft and 25 connected to said blade operating mechanism for operating the same, said operating rod extending downwardly into said sump, an opening formed longitudinally in said operating rod and terminating at a distance from the top thereof, a 30 hollow extensible member mounted in said runner shaft at a point near the upper end of said operating rod opening, a valve mounted in said extensible member and normally closing communication therethrough, a lateral bore formed 35 in the operating rod and leading from the longitudinal opening in said rod, a nut threadedly mounted in said runner shaft and operatively connected with said extensible member for moving said member inwardly and outwardly with 40 respect to said operating shaft, and a retainer threadedly mounted on said nut and having an internally threaded central opening formed therein for the reception of a nipple having an inwardly projecting element adapted to engage said 45 valve to unseat the same when the extensible member is connected to said operating rod.

2. In a hydraulic machine, a runner having a 50 hollow hub with a sump in the bottom thereof, a plurality of blades rotatably mounted in said hub, mechanism within the hub for rotating the blades, a hollow shaft connected to the hub, an operating rod disposed within said hollow shaft and connected to said blade operating mechanism, means 55 for reciprocating said operating rod to effect operation of said mechanism, said operating rod extending downwardly into said sump, a bore formed longitudinally in said operating rod, a lateral bore leading from said longitudinal bore outwardly to the exterior of said rod, and means 60 carried by said runner shaft and adapted to be connected to said lateral bore when the bottom of the operating rod is positioned adjacent the bottom of the sump for conducting fluid from said sump outwardly through said runner shaft, said 65 means being normally disengaged from said operating rod when the machine is in operation.

GEORGE A. JESSOP.
TORLEIF NORBOM.
